(57) **CLAIM**

The ornamental design for a bed sheet, as shown and described.

DESCRIPTION

FIG. 1 is a perspective view of a bed sheet illustrating a flap in a first position, the bed sheet being positioned over a mattress (not shown);

FIG. 2 is a top plan view thereof;

FIG. 3 is a bottom plan view of the bed sheet removed from the mattress;

FIG. 4 is a side view of FIG. 1;

FIG. 5 is a side view of the flap of the bed sheet in a second alternate position;

FIG. 6 is an end view thereof;

FIG. 7 is opposite end view thereof;

FIG. 8 is a plan view of the bed sheet in an unfolded position;

FIG. 9 is a perspective view of the bed sheet illustrating the flap in the second alternate position, the bed sheet being positioned over the mattress; and,

FIG. 10 is an enlarged cross sectional view taken along line “10—10” in FIG. 2, shown broken away to fit on the drawing sheet.

The broken lines showing the pillow in FIGS. 1 and 9 illustrate the environment in which the bed sheet is used and forms no part of the claimed design. The broken lines on the bed sheet in FIG. 8 are fold lines.
